COLLAR STIFFENER

Giuseppe M. M. Vaccarella, Manhasset, N. Y.

Application February 29, 1944, Serial No. 524,363

3 Claims. (Cl. 2—132)

The invention relates to devices for improving the appearance of wearing apparel and more particularly to an attachment which may be conveniently applied to the wing of a soft collar or the like to stiffen it.

According to a preferred form, the invention may comprise a generally triangular body member having a pair of arms pivoted near the upper corners thereof, the arms having offset pins rigidly secured thereto. The lower end of the body member may have an adjustable pin slidably mounted thereon. In use, the arm pins may be stuck into the hem on the underside of the collar wing and the adjustable pin may be stuck into the hem at the tip of the collar wing in such manner that the attachment is contained well within the confines of the collar so that it remains hidden. The pivoted relationship of the several parts applies a stretching or spreading force both laterally of the collar wing and lengthwise thereof imparting a smooth and attractive appearance.

The invention also consists in certain new and original features of construction and combinations of parts hereinafter set forth and claimed.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawing forming a part hereof, in which:

Fig. 1 represents a plan view of the collar stiffener shown applied to the wing of a conventional type of sofa collar, the collar being opened up to better illustrate the invention;

Fig. 2 is a side elevation of a portion of the collar as seen from the direction of the arrows 2—2 in Fig. 1 with the attachment in place;

Fig. 3 is a section through the attachment on the line 3—3 of Fig. 1;

Fig. 4 is a transverse section on the line 4—4 of Fig. 1; and

Fig. 5 is a plan of the attachment folded up for carrying around in one's pocket when not in use.

In the following description and in the claims, various details will be identified by specific names for convenience, but they are intended to be as generic in their application as the art will permit.

Like reference characters denote like parts in the several figures of the drawing.

In the drawing accompanying and forming part

of this specification, certain specific disclosure of the invention is made for purposes of explanation, but it will be understood that the details may be modified in various respects without departure from the broad aspect of the invention.

The attachment is shown applied to a wing of a soft collar of the conventional type having the usual collar band 32 and the usual turned down outer band 33, the crease being indicated by 35 and the entire collar being provided with a marginal hem or binding indicated in general by 36. The usual buttonhole is indicated by 34. Although one particular type of soft collar is shown for purposes of illustration, it will be understood that the stiffener may be applied to other types of soft collars and also to so-called semi-soft collars and even to stiff or hard collars.

The stiffener comprises a body 10 of generally triangular or V-shape having arms 11, 12 pivoted near the upper corners thereof. The arms have rigidly secured thereto pins 13, 14 having their shanks suitably secured to the arms 11, 12 and having their points 15, 16 bent and offset from the main parts of the arms.

The arms are suitably pivoted to the body 10 by pivots 17, 18 of similar construction. Each pivot comprises a rivet 19 suitably headed and countersunk in the plate-like materials of the body 10 and arms 11, 12. To control the movement of the arms with respect to the body, a suitable spring washer 20 may be interposed in suitable recesses located in the body and arm members.

At the lower end of the body 10 an adjustable pin 25 is provided, this pin being slidable in a seat or opening 26 formed in the body 10. The pin 25 may be an ordinary pin of commerce having a head 27 and a point 28. The body 10 is formed with a recess or hole 29 to accommodate the head 27 and whose edge limits the movement of the head from the operative position shown in Fig. 3, with the point 28 "out," to the inoperative position shown in Fig. 5, with the point of the pin "in."

In assembling the device in the factory the pin 25 is applied to the opening 26 in the manner shown in dot-and-dash lines in Fig. 3. If desired, the pin 25 may be permanently deformed slightly when assembling so that it will bind slightly in the opening 26 when in use. It will be understood that the spring washers 20 of the pivots also cause a slight binding. Thus, in use the arms 11, 12 can be swung easily about their pivots and yet will not accidentally swing so as to be out of control. Similarly, the adjustable pin

25 binds just enough to hold it in adjusted position although not enough to make forcible sliding of the pin by the fingers difficult.

Thus, when the pin 25 is retracted, as shown in Fig. 5, and the arms 11, 12 are folded, these parts will frictionally retain their inoperative positions whereby the various pin points are within the confines of the body 10 and will not stick the user.

To use the stiffener, it may be applied to the collar either before or after the collar is placed on the neck of the wearer, according to the desire of the wearer. The arm pins 13 and 14 will be inserted in the hem 30 on the underside of the wing. The points will pierce only the hem and not the outside ply of fabric so that the stiffener will remain hidden. The body 10 will then be pressed upwardly in such manner as to cause the arms 11, 12 to spread apart somewhat to laterally stretch the material of the wing. The place at which the arm pins are stuck into the hem is so chosen that under this condition the lower part of the body 10 occupies a position well within the confines of the tip 31 of the collar at which time the pin 25 will be moved downwardly by the user to pierce the material of the hem 30 but not the outside ply of the collar.

Thus the collar wing is under tension both laterally and lengthwise thereof, imparting a smooth appearance to the wing and preventing formation of wrinkles.

The stiffener may be made of any suitable material, either metal or plastic except for the pins and possibly the pivots and spring washers, which it might be better to make of metal. It is preferable that the material have some weight to help hold the collar wings down. The body and arms may be die cast as shown with the arm pins 13 and 14 cast in the arms and the adjustable pin hole 26 cast in the body 10. Or the body and arms may be made from sheet stock.

Thus a collar wing stiffener in the form of an attachment is provided which is inexpensive to make and simple and efficient in use. It folds up in such way as to permit easy carrying in one's pocket without danger of getting pricked by the pins. It is easily opened into operative position and applied to the collar. It is capable of use with different types and makes of collar and is also capable of use with different shapes and angles of the wing. The same stiffener may be used with practically all makes and sizes of collar.

While certain novel features of the invention have been disclosed herein, and are pointed out in the annexed claims, it will be understood that various omissions, substitutions and changes may

be made by those skilled in the art without departing from the spirit of the invention.

What is claimed is:

1. A collar stiffener for stiffening the wing of a soft collar or the like, comprising a body member having a guide at its lower part, an adjustable pin slidable in said guide, right and left arm members, pivot means connecting said arm members to the upper part of said body member, fixed pin members rigidly secured to the free ends of said arm members, said fixed pin members being adapted to engage the hem of the collar at the bottom and front edge of the wing thereof, said adjustable pin member being adapted to engage the hem at the tip of the wing.
2. A collar stiffener for stiffening the wing of a soft collar or the like, comprising a body member having a guide at its bottom, an adjustable pin slidable in said guide, right and left arm members, pivot means connecting said arm members respectively to the upper part of said body member, fixed pin members rigidly secured to the free ends of said arm members, said fixed pin members projecting in directions substantially opposite to said adjustable pin when the arm members are in operative position, said fixed pin members being laterally offset beyond the confines of said arm members, said fixed pin members being adapted to engage the hem of the collar at the bottom and front edge of the wing thereof, said adjustable pin member being adapted to engage the hem at the tip of the wing.
3. A collar stiffener for stiffening the wing of a soft collar or the like, comprising a V-shaped body member having a guide at its lower point, an adjustable pin member slidable in said guide, right and left arm members, pivot means connecting said arm members respectively to the upper corners of said body member, fixed pin members rigidly secured to the free ends of said arm members, said fixed pin members projecting in directions substantially opposite to said adjustable pin member when the arm members are in operative position, said pin members having points laterally offset beyond the confines of said arm members, said fixed pin members being adapted to engage the hem of the collar at the bottom and front edge of the wing thereof, said adjustable pin member being adapted to engage the hem at the tip of the wing, said arm members being foldable downwardly with their pin members within the confines of said body member, and said adjustable pin member being retractible so that its point is within the confines of said body member.

GIUSEPPE M. M. VACCARELLA.
